UNITED STATES PATENT OFFICE.

WINIFRED SCOTT, OF MONTREAL, QUEBEC, CANADA.

BED COVERING.

1,403,873.

Specification of Letters Patent. Patented Jan. 17, 1922.

Application filed October 16, 1920. Serial No. 417,485.

To all whom it may concern:

Be it known that I, WINIFRED SCOTT, of the city of Montreal, Province of Quebec, Dominion of Canada, have invented certain new and useful Improvements in Bed Coverings; and I do hereby declare that the following is a full, clear, and exact description thereof.

My invention relates particularly to bed covering for infants of tender age and has for its object to provide for the tucking in of the infant without danger of being subsequently uncovered by the movement of the infant; and a further object of the invention is to provide a simple and inexpensive covering having this quality and one which may be readily made by any mother or nurse and from any material whether woolen blankets, cotton sheeting, flannel or canton-flannel as circumstances may require.

To this end the invention consists of a bed covering exceeding in width more or less the height of the infant and of sufficient length to be tucked under the sleeping pad or mattress to a considerable extent. More specifically stated my improved covering comprises two parts, one of which lies upon the bed for the infant to rest upon and the other part, which may be longer, is stitched to the under part and has a pleat of sufficient width to accommodate the body of the infant with ample space for kicking, the pleat being stitched down along the bottom edge to both top and bottom parts. The upper end of the pleat has notches for the neck and arms of the infant, these notches being so formed that they may be closed by safety pins connecting the upper to the under parts close to the neck opening.

For full comprehension, however, of my invention, reference must be had to the accompanying drawings in which similar reference characters indicate the same parts, and wherein:

Figure 1 is a plan view of a bed with my invention applied thereto;

Figure 2 is a similar view to Figure 1 with my improved bed covering thrown open;

Figure 3 illustrates my improved bed covering removed;

Figure 4 is a transverse sectional view taken on line 4-4 Figure 3;

Figure 5 is a longitudinal sectional view illustrating the manner in which the upper part of the covering is pinned at the shoulder to the lower part, and

Figure 6 is a side elevation of a bed with my invention applied thereto.

The under part of the covering is indicated at *b* and the upper part at *c* while the pleat is indicated at *d*. The pleat is of sufficient dimensions to accommodate the baby with ample room for kicking and the middle of the top has a neck notch *e* and the side arm notches *f*, the notches being so cut that portions *g* of the covering are presented partially closing the arm notches and affording means by which the outer part may be pinned to the under part near the neck and consequently cover the shoulders of the infant. The under part and tucked outer part are stitched together as at *i*, the line of stitching fastening down the lower ends of the tuck, thus establishing the kicking room.

The upper or outer part *c* is preferably of sufficient length to permit its ends being tucked under the sleeping pad or mattress, to be held against being displaced by any movement of the infant; while the under part *b* may be shorter as illustrated, the upper part and connection between the parts holding the under part in place.

Although I have described the two parts of my bed covering as being stitched together, yet they may be cut from the same piece folded, or otherwise united without departing from the spirit of my invention.

What I claim is as follows:

1. A flexible textile protecting covering or blanket for an infant, such covering exceeding in width the height of the infant when reclining and consisting of under and upper parts stitched together along the lower edge, the upper part being of sufficient length to enwrap the infant and its pad or mattress and having transverse pleats for the purpose of affording accommodation for the infant.

2. A flexible textile protecting covering or
blanket for an infant, such covering exceeding
in width the height of the infant when
reclining and consisting of under and upper
5 parts stitched together along the lower edge,
the upper part being of sufficient length to
enwrap the infant and its pad or mattress
and having transverse pleats for the purpose
of affording accommodation for the infant,
10 and the upper end of the pleat having a
notch for the neck and notches for the arms,

the material between the neck and arm
notches being adapted to be fastened to the
upper edge of the under part.

15

In testimony whereof I have signed my
name to this specification in the presence of
two witnesses.

WINIFRED SCOTT.

Witnesses:

GORDON G. COOKE,
WILLIAM J. C. HEWETSON.
